PROCESS FOR PREPARING WETTING AGENTS

Walther Schrauth, Berlin-Dahlem, Germany, assignor, by mesne assignments, to "Unichem" Chemikalien Handels A.-G., Zurich, Switzerland, a corporation of Switzerland

No Drawing. Application January 24, 1934,
Serial No. 708,075. In Germany January 30,
1933

24 Claims. (Cl. 252—1)

The present invention has for an object the production of washing-, cleansing-, wetting-out and emulsifying agents by conjoint sulfonation of fat like substances and aromatic or hydroaromatic hydrocarbons or mixed aromatic-hydroaromatic hydrocarbons respectively.

As everybody knows, the sulfonates of aromatic hydrocarbons and particularly of naphthalene and of tetrahydronaphthalene, possess the property of converting substances insoluble in water into aqueous solutions (hydrotropic properties). They are therefore not merely applied as admixtures to soaps of all kinds, but also as diluents for soap-like substances such as are found in the sulfates and sulfonates of waxes, fats, oils and especially of higher molecular fatty alcohols and the like. Now, as a rule, the conditions under which the sulfonating process leads to the production of sulfonates of aromatic hydrocarbons are different from those under which an exhaustive sulfonation, of for example the higher molecular fatty alcohols, is obtained. While in sulfonating the latter one employs the lowest possible temperatures, the production of aromatic sulfonic acids occurs as a rule at temperatures of more than 100° C. Therefore it could not be expected without ado, that e. g. higher molecular alcohols might be conjointly sulfonated with aromatic hydrocarbons in such a manner that sulfates and sulfonates of higher molecular alcohols are obtained simultaneously with the sulfonates of aromatic hydrocarbons.

Now it has been found that materials of both groups can be conjointly sulfonated at low temperatures and in such a manner that even the aromatic hydrocarbons, which otherwise can be sulfonated only at higher temperatures, produce sulfonic acids even if the sulfonation is performed at the lowest possible temperatures. It is also possible to employ chlor sulfonic acid and similar sulfonating agents. One employs advantageously chloro sulfonic acid in a proportion that exceeds by about 10 to 20% the theoretically necessary proportion, the degree of purity being considered when determining the respective proportion. The aromatic hydrocarbon which at the beginning is still unsulfonated, acts as a solvent and insures even at very low temperatures a perfect sulfonation of the reaction mixture. The sulfonation, under the aforesaid conditions, is performed with quite surprising completeness so that there is no need of any separate treatment of the single components. In only a single operation one obtains a mixture of sulfonates similar to that which otherwise results

by a mechanical mixing, conjoint grinding and the like of the single components; thus one saves the cost of the machines which would be necessary for the latter operations.

Compared with the well-known method of sulfonation of higher molecular alcohols in the presence of solvents which makes possible a sulfonation at low temperatures the procedure of this invention is distinguished not only by making it possible to sulfonate the applied hydrocarbons at low temperatures but also by the simultaneous sulfonation of these hydrocarbons themselves. Moreover, by means of these hydrocarbons one obtains products which when mixed with the sulfonates serving as cleansing agents, possess most valuable properties for the textile purposes, without reacting with themselves by condensing or the like.

In the afore described way it is practicable to sulfonate higher molecular fatty or wax alcohols, their esters and ethers, fatty acids, their esters with mono- or polyhydric alcohols, particularly glycerides, and furthermore waxes, fat-like substances and the like, but the alcohols or fatty acids respectively on which the said compounds are based, should contain no less than 8 carbon atoms in the molecule. Among the alcohols to be considered there may be mentioned first of all the dodecyl-, myristyl-, cetyl-, octadecyl- and the oleyl alcohol; among the fatty acids the oleic and ricinolic acid are particularly recommendable. The hydrocarbons suitable for the performing of the present procedure must have a low point of solidification and they must themselves be sulfonable, thus to secure a thorough sulfonation even at low temperatures. The sulfonates made of them are to be fit for converting substances insoluble in water into aqueous solutions.

The products obtained according to the present method distinguish themselves by an extraordinary stability and are superior to the preparations obtained by mixing the single components. The degree of sulfonation is considerably higher than that obtained by the separate sulfonation of the single components. They are fast to boiling in hard water of 50° (German hardness degree) and form solutions which are clear even at very low temperatures. Their fastness to acids is excellent. Owing to the low reaction temperatures which are applied, the reaction of the sulfonating agents is very mild and, therefore, the thus obtained products are of a very light color.

Example 1

1400 g. of oleyl alcohol of the iodine number 90 and of a congealing-point of +2° are mixed with 500 g. of tetrahydronaphthalene. Into this mixture 1120 g. of chlorosulfonic acid are gradually stirred in the course of about 5 hours at a temperature of -5° to +5° under constant cooling. By the neutralizing with a diluted solution of caustic soda one obtains about 4500 g. of a reaction product containing approximately 30% of fat. The clarification point of 2% solutions is at about 20°.

Example 2

15 To a mixture consisting of 420 parts by weight of sperm oil and 260 parts by weight of tetrahydrophenanthrene (or 150 weight parts of cymol respectively), one adds gradually under stirring 280 parts by weight of chlorosulfonic acid at a 20 temperature of -3° to +5° C. taking care for a good cooling and then one continues to stir for three hours. The further treatment is carried out as per Example 1. The thus obtained reaction product suits well for the production of 25 emulsifying and wetting-baths.

Example 3

1500 g. of dioleyether of the iodine number 92 are mixed with 500 g. of tetrahydronaphthalene 30 and cooled down to about 0° C. Into this mass 1050 g. of chlorosulfonic acid are gradually dropped in the course of about 4-5 hours while continuing the constant cooling and under a regular stirring. The reaction being terminated one 35 neutralizes with a diluted solution of caustic soda and the thus obtained product shows excellent capillary-active properties. It is also allowed to substitute other ethers for the dioleyether, particularly mixed ones such as lauryl-mono-glycol-ether, cetyl-mono-glycerineether and the like. 40

Example 4

1000 g. of oleic acid of a iodine number of 85 are mixed with 400 g. of tetrahydromethylnaphthalene, whereupon the mixture is cooled down 45 to a temperature lying between -5° and +5° C. Into this mixture, which is kept at the said temperature, one gradually drops 700 g. of chlorosulfonic acid. The reaction product obtained after 50 terminating the reaction and after neutralization is advantageously applied for washing- and cleansing baths.

The term "sulfonation" as found in the claims 55 is used in the broad sense to include both true sulfonation and sulfation.

The terms "sulfonate", "sulfonation" and the like are used in the broad sense to define the formation of sulfuric acid esters as well as the formation of true sulfonic acid, except where it 60 is clear that the true sulfonation is intended.

What I claim is:-

1. As a product of manufacture the composition of sulfonated sperm oil with tetrahydrophenanthrene sulfonic acid, applicable as wetting-out-, washing-, cleansing- and emulsifying agent.

2. As a product of manufacture the composition of sulfonated dioleyl ether with tetrahydronaphthalene sulfonic acid, applicable as wetting-out-, washing-, cleansing- and emulsifying agent.

3. As a product of manufacture the composition of sulfonated oleic acid with tetrahydromethylnaphthalene sulfonic acid, applicable as wetting-out-, washing-, cleansing- and emulsifying agent.

4. The manufacture of washing, cleansing, wetting-out and emulsifying agents characterized by the conjoint sulfonation of an aliphatic compound selected from the group consisting of the primary aliphatic alcohols having 8 or more carbon atoms in the molecule, the ethers of these alcohols with the same or other primary aliphatic alcohols, the esters of these alcohols with primary aliphatic carboxylic acids, primary aliphatic carboxylic acids having 8 or more carbon atoms in the molecule and the esters of these acids with primary mono- and poly-hydric aliphatic alcohols, and of an aromatic hydrocarbon without the formation of condensation products between both components.

5. The manufacture of washing, cleansing, wetting-out and emulsifying agents characterized by the conjoint sulfonation of a primary aliphatic alcohol having 8 or more carbon atoms in the molecule and of an aromatic hydrocarbon without the formation of condensation products between both components.

6. The manufacture of washing, cleansing, wetting-out and emulsifying agents characterized by the conjoint sulfonation of primary aliphatic alcohol having 12 to 18 carbon atoms in the molecule and of an aromatic hydrocarbon at a temperature of the order of -5 to +5° C. without the formation of condensation products between both components.

7. The manufacture of washing, cleansing, wetting-out and emulsifying agents characterized by the conjoint sulfonation of primary aliphatic unsaturated alcohol having 12 to 18 carbon atoms in the molecule and of an aromatic hydrocarbon at a temperature of the order of -5 to +5° C. without the formation of condensation products between both components.

8. The manufacture of washing, cleansing, wetting-out and emulsifying agents characterized by the conjoint sulfonation of oleyl alcohol and of an aromatic hydrocarbon without the formation of condensation products between both components.

9. The manufacture of washing, cleansing, wetting-out and emulsifying agents characterized by the conjoint sulfonation of an ether of primary aliphatic alcohols, at least one of which alcohols has 8 or more carbon atoms in the molecule and of an aromatic hydrocarbon without the formation of condensation products between both components.

10. The manufacture of washing, cleansing, wetting-out and emulsifying agents characterized by the conjoint sulfonation of ethers of primary aliphatic alcohols both of which have 8 or more carbon atoms in the molecule and of an aromatic hydrocarbon without the formation of condensation products between both components.

11. The manufacture of washing, cleansing, wetting-out and emulsifying agents characterized by the conjoint sulfonation of di-oleyl ether and of an aromatic hydrocarbon without the formation of condensation products between both components.

12. The manufacture of washing, cleansing, wetting-out and emulsifying agents characterized by the conjoint sulfonation of an ester of a primary aliphatic alcohol and a primary aliphatic acid at least one of which components has 8 or more carbon atoms in the molecule without the formation of condensation products between both components.

13. The manufacture of washing, cleansing,

wetting-out and emulsifying agents characterized by the conjoint sulfonation of esters of primary aliphatic acid having 8 or more carbon atoms in the molecule with primary aliphatic alcohol and of an aromatic hydrocarbon without the formation of condensation products between both components.

14. The manufacture of washing, cleansing, wetting-out and emulsifying agents characterized by the conjoint sulfonation of esters of primary aliphatic alcohol having 8 or more carbon atoms in the molecule with primary aliphatic acid and of an aromatic hydrocarbon without the formation of condensation products between both components.

15. The manufacture of washing, cleansing, wetting-out and emulsifying agents characterized by the conjoint sulfonation of esters of primary aliphatic alcohol having 8 or more carbon atoms in the molecule with primary aliphatic acid having 8 or more carbon atoms in the molecule and of an aromatic hydrocarbon without the formation of condensation products between both components.

16. The manufacture of washing, cleansing, wetting-out and emulsifying agents characterized by the conjoint sulfonation of an unsaturated wax ester and of an aromatic hydrocarbon without the formation of condensation products between both components.

17. The manufacture of washing, cleansing, wetting-out and emulsifying agents characterized by the conjoint sulfonation of sperm oil and of an aromatic hydrocarbon without the formation of condensation products between both components.

18. The manufacture of washing, cleansing, wetting-out and emulsifying agents characterized by the conjoint sulfonation of an aliphatic compound selected from the group consisting of the primary aliphatic alcohols having 8 or more carbon atoms in the molecule, the ethers of these alcohols with the same or other primary aliphatic alcohols, the esters of these alcohols with primary aliphatic carboxylic acids, primary aliphatic carboxylic acids having 8 or more carbon atoms in the molecule and the esters of these acids with primary mono- and poly-hydric aliphatic alcohols, and of hydrocarbons of the group consisting of naphthalene, tetrahydro-naphthalene, tetra hydro phenanthrene, tetrahydro methyl naphthalene and cymol at low temperatures without the formation of condensation products between both components.

19. The manufacture of washing, cleansing, wetting-out and emulsifying agents characterized by the conjoint sulfonation of an aliphatic compound selected from the group consisting of the primary aliphatic alcohols having 8 or more carbon atoms in the molecule, the ethers of these alcohols with the same or other primary aliphatic alcohols, the esters of these alcohols with primary aliphatic carboxylic acids, primary aliphatic carboxylic acids having 8 or more carbon atoms in the molecule and the esters of these acids with primary mono- and poly-hydric aliphatic alcohols and of aromatic hydrocarbons of the naphthalene series at a temperature of the order of -5 to +5° C. without the formation of condensation products between the components.

20. The manufacture of washing, cleansing, wetting-out and emulsifying agents characterized by the conjoint sulfonation of an aliphatic

compound selected from the group consisting of the primary aliphatic alcohols having 8 or more carbon atoms in the molecule, the ethers of these alcohols with the same or other primary aliphatic alcohols, the esters of these alcohols with primary aliphatic carboxylic acids, primary aliphatic carboxylic acids having 8 or more carbon atoms in the molecule and the esters of these acids with primary mono- and poly-hydric aliphatic alcohols and of hydronaphthalene hydrocarbons without the formation of condensation products between both components.

21. The manufacture of washing, cleansing, wetting-out and emulsifying agents characterized by the conjoint sulfonation of an aliphatic compound selected from the group consisting of the primary aliphatic alcohols having 8 or more carbon atoms in the molecule, the ethers of these alcohols with the same or other primary aliphatic alcohols, the esters of these alcohols with primary aliphatic carboxylic acids, primary aliphatic carboxylic acids having 8 or more carbon atoms in the molecule and the esters of these acids with primary mono- and poly-hydric aliphatic alcohols and of aromatic hydrocarbons capable of being sulfonated to form emulsifying agents without the formation of condensation products between both components.

22. The manufacture of washing, cleansing, wetting-out and emulsifying agents characterized by the conjoint sulfonation of an aliphatic compound selected from the group consisting of the primary aliphatic alcohols having 8 or more carbon atoms in the molecule, the ethers of these alcohols with the same or other primary aliphatic alcohols, the esters of these alcohols with primary aliphatic carboxylic acids, primary aliphatic carboxylic acids having 8 or more carbon atoms in the molecule and the esters of these acids with primary mono- and poly-hydric aliphatic alcohols and of tetrahydronaphthalene without the formation of condensation products between both components.

23. The manufacture of washing, cleansing, wetting-out and emulsifying agents characterized by the conjoint sulfonation of an aliphatic compound selected from the group consisting of the primary aliphatic alcohols having 8 or more carbon atoms in the molecule, the ethers of these alcohols with the same or other primary aliphatic alcohols, the esters of these alcohols with primary aliphatic carboxylic acids, primary aliphatic carboxylic acids having 8 or more carbon atoms in the molecule and the esters of these acids with primary mono- and poly-hydric aliphatic alcohols and of tetrahydro phenanthrene without the formation of condensation products between both components.

24. The manufacture of washing, cleansing, wetting-out and emulsifying agents characterized by the conjoint sulfonation of an aliphatic compound selected from the group consisting of the primary aliphatic alcohols having 8 or more carbon atoms in the molecule, the ethers of these alcohols with the same or other primary aliphatic alcohols, the esters of these alcohols with primary aliphatic carboxylic acids, primary aliphatic carboxylic acids having 8 or more carbon atoms in the molecule and the esters of these acids with primary mono- and poly-hydric aliphatic alcohols and of tetrahydro methyl naphthalene without the formation of condensation products between both components.

WALTHER SCHRAUTH.
